UNITED STATES PATENT OFFICE

GUY L. MATTHEWS, OF CHICAGO, ILLINOIS, ASSIGNOR TO HARRY L. DIEHL, OF CHICAGO,
ILLINOIS

HOOK FOR A GUT STRING POLISHING MACHINE

Application filed November 5, 1928. Serial No. 317,461.

This invention pertains to the general class of devices used in polishing machines, and particularly to a hook used in a machine for polishing gut strings. An object of applicant's invention is the production of a hook for the purposes set forth, whereby the strings may be rotated about its longitudinal axis. A further object of applicant's invention is the production of a device as set forth, whereby the string may be readily attached and detached. A further object is the production of a hook of the kind set forth whereby the vibration of the string during rotation of same is reduced to a minimum. A further object is the production of a hook as set forth that is of low cost, readily manufactured, economical to produce, easily installed and highly satisfactory for its intended purpose.

Many other objects and advantages of the construction herein shown and described will be obvious to those skilled in the art from the disclosure herein given. To this end my invention consists in the novel construction, arrangement and combination of parts herein shown and described, and more particularly pointed out in the claims. Applicant's hook is adapted to be used in a polishing apparatus such as is disclosed in applicant's pending application Serial No. 139,544, filed October 4, 1926. When the string is rotated about its longitudinal axis, unbalanced forces, vibration, slapping of the strings, and any tendency to polish one side of the string more than the other, as well as other difficulties are greatly diminished. The hook described in this application is particularly adapted to be used in a machine wherein a plurality of strings are polished at the same time, same being arranged side by side in the machine. By having the string more or less balanced about its longitudinal axis, interference between the strings is avoided.

In the drawing, wherein like reference characters indicate like or corresponding parts:

Fig. 1 is a fragmentary plan view of a machine having applicant's invention incorporated therein.

Fig. 2 is a section taken on line 2—2 of Fig. 1;

Fig. 3 is a fragmentary plan view of one end of the novel hook showing a loop in dotted lines attached thereto;

Fig. 4 is a fragmentary elevation of one end of the hook showing the string in dotted lines secured to the hook by means of the knot between the string and the loop;

Fig. 5 is an end view of the hook;

Fig. 6 is a view taken on line 6—6 of Fig. 4.

Referring to the drawing, 1 shows a polishing apparatus comprising a frame 2 upon which is mounted transversely extending supports 3. In the members 3 are preferably mounted wooden blocks 4 which support a drive shaft 5 and a plurality of shorter shafts 60. The shaft 5 is belted or otherwise connected as shown at 60 to a motor or other driving means, not shown.

As clearly shown in Fig. 2, the shaft 5 extends the full width of the machine and has a hook 7 projecting from one end thereof. A gut string 8 is shown attached to hook 7 by means of a loop 9. The loop 9 is attached to the string 8 preferably by means of a knot. At 10 are shown a plurality of bearings for the shaft 5. The bearings are preferably mounted in recesses in blocks 4 which may be wood, babbitt or other suitable material in order to decrease vibration and noise. The shaft 5 has a gear 11 secured thereto which meshes with a gear 12 attached to the adjacent shaft 6. Each of the parallel shafts 6 have a gear 12 secured thereto, said gears arranged to form a train such that each of the shafts 6 are rotated with the shaft 5.

In Fig. 1 it is clearly seen that the hooks 13 on the shafts 6 project from one side of the frame similar to the hook 7 on shaft 5. The hook 7 and hooks 13 are formed in accordance with the invention disclosed in this application and shown in detail in Figs. 3 to 6 inclusive. Hook 7 and hooks 13 are identical and, for the purposes of this application, in Figs. 3 to 6 inclusive will be given the numeral 14. The hook end of each shaft is preferably round with the portion 15 thereof cut away beyond the longitudinal axis of the shaft, as clearly shown in Figs. 3 and 4. The tip 16 is left intact and preferably rounded as shown at 17. The tip 16 is provided with a

countersunk aperture 18 along the longitudinal axis of the shaft and a slot 19 cut downward through the tip to meet said countersunk portion. Two projecting fingers 20 and 21 are thus formed. A longitudinal groove 22 is cut in the side of the finger 20 and a longitudinal groove 23 is cut in the side of the finger 21. The inner upper portions of the fingers are preferably rounded as shown at 24 in Fig. 4. Other parts of the hook are preferably rounded in order that there are no sharp edges to cut the string or loop.

In operation the loop may be thrown over the fingers as shown in Fig. 3, the sides of the loop fitting in the grooves 22 and 23. It will be noted that the grooves 22 and 23 are diametrically opposite and that the centers of curvature of same are on a line which intersects the longitudinal axis of the shaft. The string 8 is thus rotated about its longitudinal axis. It is understood that there is a duplicate machine such as is shown in Figs. 1 and 2 at the opposite end of the string 8 to secure said end of the string. String 8 of course is held taut between the two machines. The machines are preferably operated by synchronous motors such that each pair of oppositely disposed hooks rotate at the same speed and in synchronism.

Should the string 8 be slightly off center due perhaps to an inequality in the knot 25 between the loop 9 and the string 8, the string may be secured by means shown in Fig. 4 wherein the knot 25 itself is held by the fingers 20 and 21, the string 8 passing down into the aperture 18 through the slot 19. The countersunk portion 18 allows the end of the string at the knot freedom of movement and thereby compensates for any slight deviation from alignment of the oppositely disposed machines 1 holding opposite ends of the string 8. The string 8 may be secured to the hook in a still different manner such as disclosed in Fig. 2, wherein the loop 9 is passed over the hook and the sides of the loop passed downward through the slot 19, securing the loop in the position clearly shown in Fig. 2. It is thus seen that correct alignment of the string may be easily and quickly effected and that the string may be readily attached and detached from the hook. The slight deviation from alignment in any one of the positions is so small as to be of small consequence when compared to an ordinary hook used for this purpose. It is of course understood that the machine partially shown is capable of handling several strings at one time. It is thus seen that a highly novel device has been produced satisfactory for its intended purposes.

Having thus described my invention, it is obvious that various immaterial modifications may be made in the same without departing from the spirit of my invention; hence I do not wish to be understood as limiting myself

to the exact form, construction, arrangement and combination of parts herein shown and described, or uses mentioned.

What I claim as new and desire to secure by Letters Patent is:

1. In a hook for polishing machines of the kind described, a shaft having a fixed axis of rotation, said shaft having a recess extending to beyond the center line and near one end, said end portion having an axially disposed longitudinally extending countersunk aperture, a radially disposed slot in said end portion opening into said aperture and extending to the lateral face of the hook, and oppositely disposed longitudinally extending grooves in the outer surface of said end portion. 70 75 80

2. In a device of the class described, the combination of a shaft having a fixed axis of rotation, and a hook adjacent one end thereof and rigid with respect thereto, said hook comprising a pair of fingers having overhanging portions formed therein and oppositely disposed longitudinally extending grooves formed in the outer faces thereof in a plane common to each other and to the axis of rotation of said shaft. 85 90 95

3. In a hook for polishing machines of the kind described, a shaft having a fixed axis of rotation, said shaft having a recess extending to beyond the center line thereof and forming a portion of reduced dimensions at one side of the shaft adjacent one of its end portions, said end portion having an axially positioned longitudinally disposed aperture formed therein extending into said recess and having a radially disposed slot opening into said aperture and extending to the lateral face of said end portion at the opposite side of the aperture from the portion of reduced dimensions formed on said shaft. 100 105 110

In testimony whereof, I have hereunto signed my name.

GUY L. MATTHEWS.
